[57] **ABSTRACT**

An educational toy adding machine having a plurality of rotatable discs with indicia on one face thereof viewable through windows in the housing of the machine. Driver discs coaxially mounted and rotatable with the viewed discs have pins extending outwardly from the face thereof. A driving spindle is biased upwardly above the pins on the driven discs. A large key extends through said housing and contacts the upper end of the spindle. The upper surface of the spindle is inclined so that depression of the key moves the spindle downwardly and laterally so as to contact said pins.

EDUCATIONAL TOY ADDING MACHINE

This application relates generally to adding machines and more specifically to an educational toy adding machine for use by very young people.

Adding machines and the mechanisms used therefor are well known and have been used for many applications. However, the adding machines which are on the market today cannot be used by small children. This is primarily due to the fact that the buttons are too small, and the figures which are read are too small. Further, the value of the machine renders it undesirable for use in teaching small children in basic mathematics and in the use of such adding machines.

Accordingly, it is an object of this invention to provide an adding machine which may be used by small children due to its uncomplicated nature and the large size of the mechanical operating equipment.

It is a further object of this invention to provide a child's educational adding machine which has a simple mechanism which may be economically produced for the purposes intended.

These and other objects of the invention will become apparent from the following description when taken in conjunction with the drawings wherein

FIG. 1 is a perspective view of the exterior housing for a preferred embodiment of the present invention;

FIG. 2 is a partial sectional view taken through the lines 2—2 of FIG. 1;

FIG. 3 is a sectional view taken along the lines 3—3 of FIG. 1;

FIG. 4 is a partial sectional view of the basic operating mechanism of the present invention;

FIG. 5 is an exploded view of the means for connecting the basic parts of the mechanism of the present invention;

FIGS. 6A and 6B are plan views illustrative of the mechanism as it moves the wheels of the adding machine; and

FIG. 7 is a partial view illustrating the operation of the actuator shaft.

Broadly speaking, the present invention comprises an adding machine having a plurality of discs representative of the units, tens, hundreds, etc. as desired for the size of the machine. Each disc has a fixed number such as units, tens and hundreds on one face thereof, which numbers are visible from the housing enclosing the discs. Associated drive discs are provided with a series of pins extending perpendicular thereto on either side thereof. Each drive disc has ten pins extending on one side thereof and all but the unit disc have ten pins extending perpendicularly to the disc on the other side thereof. The drive discs carrying the pins are spaced a fixed distance away from the discs which carry the numerals on their outer face. An actuating spindle is associated with each of the discs and extends upwardly therefrom and is biased in a direction away from the first set of pins. The spindle terminates in its upper end in a head having an inclined face. The inclined face rests within a large rectangular housing open at the bottom thereof which constitutes the button or key for actuating the mechanism itself. When the button is depressed, the spindle is driven downwardly against the bias of the spring and is tilted toward the drive disc and the pins by means of a camming action of the key against the inclined face of the button. The unit wheel

has a finger which, when the wheel has progressed through ten steps, contacts the second set of pins on the second wheel so as to move it one-tenth of its rotation. The second wheel has the same finger which co-acts with the third wheel and so on if more than three wheels are used.

Turning now more specifically to the drawings, there is shown a basic adding machine 11 which includes a housing 13 and a rotatable handle 15 mounted on the housing in a well-known manner. Housing 13 has a front panel 17 which contains three windows 19, 21 and 23. At the top of the machine are three buttons or keys 25, 27 and 29 which are depressable so as to actuate the mechanism in a manner which will be explained in conjunction with the other drawings.

FIG. 2 is a partial sectional rear view of the inner part of the device of FIG. 1. It will be seen that the key 25 co-acts with the actuating spindle 31. It is to be noted that each of the keys have an associated spindle. However, since they each operate in the same manner only one is shown for purposes of clarity.

Below each key are large circular discs 33, 35 and 37. These discs have indicia such as 1 through 9 for the units, 10 through 99 for the second disc, etc. printed on the front face as indicated in FIG. 1 so that the indicia appear in the windows 19, 21 and 23.

Discs 33, 35 and 37 are mounted for rotation about axles 39, 41 and 43. At a spaced distance from the large discs there are mounted on the axles smaller discs 45, 47 and 49 respectively. The spacing between the discs is more clearly shown in FIG. 3.

On the backside of each disc is a series of ten pins 51, 53 and 55 while on the interior face of each of the second and third discs are a further set of ten pins 54 and 56. It will also be noted that on the first and second discs there are fingers 58 and 60 respectively.

Fingers 58 and 60 are integral with their respective discs and actuate the associated adjoining discs through the series of pins 54 and 56. Thus, for each full rotation of disc 45, disc 47 is rotated one-tenth of its full rotation. The same relationship exists between discs 47 and 49.

Turning now to FIGS. 3 and 4, there is shown more clearly the positioning of the large disc 35 with respect to the smaller disc 47. In the particular showing these discs are mounted on the axle and form a coupling 57 so that smaller disc 47 may be press fit on larger disc 35 and rotate therewith.

An intermediate panel 59 is secured to or is integral with the housing 27. This intermediate panel provides a channel 60' for each of the actuating spindles 69. As can be seen, the channel 60' is wider than the actual dimension of the shaft 69 of the actuating spindle 32.

The shaft 69 (FIG. 4) terminates in its lower end in a flat bearing surface and terminates in its upper end in a head 73 having an inclined surface 75.

As the key 27 is depressed in the direction shown by the arrow, the pressure overcomes the bias of circular spring 77 so as to force the actuating spindle downwardly. At the same time due to a camming action, the downward pressure on the key 27 forces the head 73 to tilt due to configuration of the inclined 75. This tilting action moves the lower face 71 of the actuating spindle in a counterclockwise direction as it is being pushed downwardly so that it will contact the pin

53 and rotate the disc one-tenth of its total rotation. The position of the actuating spindle in its depressed position is shown in FIG. 7.

FIG. 5 is an exploded view showing the associated structure of drive disc 47 and retaining spring 81. The 5 function of spring 81 is shown in FIGS. 6a and 6b. Spring 81 is press fit at one end over peg 83 which may be integral with wall 59. Abutment 85, which may also be integral with wall 59, limits the movement of the spring 81.

Referring to FIGS. 6a and 6b, the terminal end of spring 81 is formed in a V-shape 82 which normally fits between adjacent pins 51. It is held in this position by means of abutment 85. As spindle 69 is driven downwardly, the movement of pins 51 bend the spring so as to allow a pin to pass over the V-shape 82 and, thus, advance the wheel one-tenth of the full rotation. Stop 87 is provided so as to limit the downward movement of spindle 69.

The primary purpose of the rotational movement of the spindle as shown in FIG. 7 is to assure that the spindle, upon release, will move away from the pins so as to avoid any possible counter-rotational force.

The present invention provides a simple and inexpensive educational toy. Further, due to the mechanism which allows for the use of large keys, very young children can easily operate the device.

The above description and accompanying drawings are illustrative only and the invention is to be limited 30 only by the scope of the following claims.

We claim:

1. An educational toy adding machine comprising a housing, a plurality of viewing windows in said housing, 35 a plurality of rotatable discs within said housing equal in number to said windows, said discs having indicia thereon and readable through said windows, a driving disc mounted coaxially with said rotatable 40 discs,

each of said driving discs having a plurality of pins extending outwardly from one face thereof, said pins being incrementally spaced so as to form a circle,

an actuating spindle extending upwardly and outwardly from said housing above said pins of each of said driving discs, a spring means for biasing said spindles away from said pins,

a depressable hollow key member extending from said housing at the upper end of said actuating spindles whereby depression of said keys move said spindles so as to overcome said bias and contact said pins, and

resilient means mounted within said housing for maintaining said disc in a fixed position, said resilient means being overridden when said spindle contacts said pins.

2. The machine of claim 1 further comprising means secured to and rotatable with said discs whereby one full rotation of one disc moves the adjacent disc one-tenth of a full rotation.

3. The machine of claim 2 wherein said means secured to said discs comprises, a finger mounted on said face of said one disc, and a plurality of pins extending outwardly from the other face of said adjacent disc, said finger contacting one of said pins on said other face during each full rotation of said one disc.

4. The machine of claim 1 further comprising a channel enclosing each of said actuating spindles, said channel being of a greater dimension than said spindles,

a head at the upper end of each spindle, said head having an inclined upper surface whereby depression of said key moves the lower end of said spindle laterally against the bias of said spring and toward said pins, and release of said key allows said spring to move said lower end of said spindle laterally away from said pins.
